UNITED STATES PATENT OFFICE.

JOHN M. BROWN, OF HAMILTON, ONTARIO, CANADA.

SHELL-MARKING MACHINE.

1,253,463.

Specification of Letters Patent. Patented Jan. 15, 1918.

Application filed October 29, 1915. Serial No. 58,733.

To all whom it may concern:

Be it known that I, JOHN MOOTERY Brown, of the city of Hamilton, in the county of Wentworth, Province of Ontario,

5 Dominion of Canada, have invented certain new and useful Improvements in Shell-Marking Machines, of which the following is the specification.

10 My invention relates to improvements in shell marking machines, and the object of the invention is to devise a machine for marking the base of shells with the required data, in which the pressure is imparted gradually to each individual type, thereby

15 eliminating all crushing strain tending to deform the type, and in which the depth of the impression may be regulated; and it consists essentially of a marking chuck secured to the base of the shell and carrying

20 individual type slugs, a saddle holder in which the body of the shell rests, a pressure member bearing against the nose of the shell, and a revolving pressure chuck designed to successively bear against each in-

25 dividual type piece carried in the marking chuck, as hereinafter more particularly explained by the following specification.

Figure 1 is a side elevation of my machine showing the marking chuck, pressure member and revolving pressure member in section.

30 Fig. 2 is a cross-sectional view on line $x-y$, Fig. 1.

Fig. 3 is an enlarged perspective detail of the marking chuck.

Fig. 4 is a detail of one of the type pieces in side elevation.

In the drawings like figures of reference indicate corresponding parts.

40 1 indicates the bed of the machine. 2 indicates the base of the saddle member which is slidably secured in position by screws 2^x on the slideway 1^x forming part of the base of the machine. 3 indicates the saddle which

45 extends upwardly from the base 2 and is provided with a semi-octagonal recess 3^x extending longitudinally of the machine. 3' indicates a series of grub screws which are threaded into each flat face 3², 3³, and 3⁴ of

50 the recess 3^x and on which the body of the shell 4 is designed to rest when in position.

55 5 indicates a cap member also provided with a semi-octagonal recess 5^x opposing the recess 3^x and also provided with grub screws 5^x bearing against the upper peripheral portion of the shell when the cap is in the

closed position. The cap 5 is pivoted on a hinge pin 5^z extending through the lugs 3^z forming part of the saddle piece 3 and the lug 5^z forming part of the cap.

60

6 indicates a clamping member comprising a link 6^x pivoted to the projecting portion of the saddle piece 3 at its lower end and extending upwardly through the notch 5^z formed in the outwardly extending flange 5^z of the cap 5. 6' indicates a lever pivoted at its inner end to the upper end of the link 6^x and provided with a depending eccentric portion 6^z bearing against the flange portion 5^z of the cap 5.

65

Although I have shown this form of clamping means it will, of course, be understood that various other means might be employed for accomplishing the same purpose.

70

7 indicates my marking chuck which comprises an outer annular member 7^x secured by a set-screw 7' to the base of the shell (as shown clearly in Fig. 1 of the drawings) and a central portion 8 located concentrically within the annular portion 7^x so as to form 80 an intervening annular space 7^z located between the portion 7^x and the portion 8. 9 indicates the type slugs provided with notches 9^x. The type slugs 9 are set in the annular space 7^z in annular series with the 85 notch 9^x facing outwardly.

75

10 and 11 indicate semi-circular plates which are placed against the base of the annular member 7^x so that its inner peripheral portion extends into the notches 9^x of 90 the type 9. It will be seen by referring particularly to Fig. 1 that the plates 10 and 11 are thin plates so as to permit of the longitudinal movement of the type 9 within the annular space 7^z. 12 indicates intervening 95 blocks which are inserted in the annular space 7^z between each set of type forming a word or complete number. 12^x indicate securing screws extending through the blocks 12 into 100 the central solid portion 8 of the marking chuck. 11^x indicate screws by which the plates 10 and 11 are connected to the base of the member 7^x.

105

13 indicates a pressure member. 14 indicates a standard having an internal thread. 15 indicates a threaded spindle extending through the standard 14 and provided with a hand-wheel 16. 18 indicates a supplemental standard extending upwardly from 110 the base 2 of the saddle member. 18^x indicates a recess formed in the outer side of

the standard 18 into which the end of the spindle 15 extends. 15* indicates an annular groove formed in the end of the spindle 15. 15' indicates an annular plate extending into the groove 15* and secured to the standard 18 by screws 15*. 19 indicates a block of babbitt secured to the inner face of the standard 18 by screws 19*, such block being provided with a tapered recess 19' into which the nose of the shell 4 fits. 20 indicates a suitably driven shaft journaled in standards 21 and 22. 23 indicates a rotating pressure member comprising a central hub member 24 and an annular outer member 25 secured to the hub member so as to form recesses 26. 27 indicates a pin which extends diametrically through the members 25, 24 and inner end of the shaft 20, being secured in position by any suitable means. 28 indicate rollers journaled upon the pin 27 at diametrically opposite points of the revolving pressure member 23 and in such a position as to bear against the outer end of the type slugs 9 extending from the marking chuck 7. 29 indicates a ball-bearing member located between the rotary pressure member 23 and the standard 22.

Having described the principal parts involved in my invention I will briefly describe the operation of the same.

The marking chuck is first secured to the base of the shell by means of the set-screw 7. The shell is then placed in the saddle 3 upon the inwardly projecting grub screws 3' and with the nose of the shell extending into the recess 19' of the block 19. The grub screws 3' are adjusted so as to insure the proper horizontal alinement of the shell when in position. The cap 5 is then closed down upon the top of the shell and clamped in position by means of the lever 6' thereby securing the shell in a stationary position. The shaft 20 is then rotated so that the rollers 28 are carried successively over the outwardly projecting ends of the type 9. The band-wheel 16 is then turned so as to exert pressure on a line parallel with the longitudinal axis of the shell thereby carrying the shell, saddle member and standard 18 longitudinally toward the rotary pressure member 23 thereby gradually increasing the pressure between the rollers 28 and the outer end of the type 9 so as to gradually force them forward against the base of the shell to form the impression.

It will be seen that the type 9 are arranged in annular series and that, therefore, the rollers 28 travel successively over the type and, therefore, form the impression not by one single pressure but by a series of comparatively light pressures repeated as the rollers 28 make their revolutions over the type.

It will be readily understood that if an impression is made by one operation or by

great pressure made instantaneously that there would be a tendency to crush the type and thereby destroy its usefulness. By my machine the pressure is exerted gradually and successively on each of the type members and, therefore, the impression is gradually made and any danger of crushing the type eliminated.

What I claim as my invention is:

1. In a shell marking machine, the combination with the shell holder, and a marking chuck adapted to be secured to the base of the shell and to carry a series of suitable type slugs, of means for gradually exerting pressure successively on each type piece to 75 form an impression on the base of the shell.

2. In a shell marking machine, the combination with the shell holder, of a marking chuck secured to the base of the shell, an annular series of type slugs carried by the marking chuck in contact at their inner ends with the base of the shell, a rotating member traveling successively over the outer ends of the type slugs, and means for gradually forcing the shell longitudinally toward 85 such rotating member.

3. In a shell marking machine, the combination with the shell holder, of a marking chuck secured to the base of the shell, an annular series of type slugs carried by the marking chuck in contact at their inner ends with the base of the shell, a rotating member traveling successively over the outer ends of the type slugs, a standard carried by the shell holder, a soft metal block carried by the standard and having a recess into which the nose of the shell fits, and means for forcing the shell holder longitudinally toward the rotating pressure member. 95

4. In a shell marking machine, the combination with the shell holder, of a marking chuck secured to the base of the shell, an annular series of type slugs carried by the marking chuck in contact at their inner ends with the base of the shell, a rotating member traveling successively over the outer ends of the type slugs, a standard carried by the shell holder, a soft metal block carried by the standard and having a recess into which the nose of the shell fits, a stationary standard having an internally threaded portion in axial alinement with the longitudinal axis of the shell, and a spindle threaded thereinto and bearing at its inner end against the standard of the shell holder and provided 100 with a hand-wheel. 110

5. In a shell marking machine, the combination with the shell holder, of means for gradually forcing the shell holder longitudinally, a marking chuck secured to the base 115 of the shell, an annular series of type carried by the marking chuck and bearing at their inner ends against the base of the shell and projecting at their outer ends from the marking chuck, a rotating shaft jour- 120 125 130

- naled in suitable bearings, and a roller carried by the shaft and designed to bear against the outer end of the type and to travel in a circular path thereover as the shaft rotates.
6. In a shell marking machine, the combination with the shell holder, of means for gradually forcing the shell holder longitudinally, a marking chuck secured to the base 10 of the shell, an annular series of type carried by the marking chuck and bearing at their inner ends against the base of the shell and projecting at their outer ends from the marking chuck, a rotatable shaft journaled in suitable bearings, a pressure member carried by the inner end of the rotating shaft, a pin extending diametrically therethrough, and rollers journaled on the pin in contact with the outer ends of the type.
- 20 7. In a device of the class described, a marking chuck comprising an inner circular member, an outer annular member forming an annular intervening space, type inserted in such annular space and adapted to move independently longitudinally thereof, means for limiting the independent longitudinal movement of the type, and means for securing the marking chuck to the shell.
8. In a device of the class described, a marking chuck comprising an inner circular member, an outer annular member forming an annular intervening space between the inner circular member and the annular member, a series of type pieces located in such 35 annular space, means for securing the inner circular member and outer annular member together so as to allow of free longitudinal movement of the type within such space, means for limiting the movement of such type, and means for securing the marking 40 chuck to the shell.
9. In a device of the class described, a marking chuck comprising an inner circular member, an outer annular member forming an intervening annular space, an annular 45 series of type pieces inserted within such annular space and having notches in their outer longitudinal edges, means for connecting the inner circular member with the outer annular member adapted to allow of free 50 longitudinal movement of the type within such space, means for securing the marking chuck to the shell, and a plate member secured to the back of the annular member and extending into the notches of the type 55 pieces to limit the longitudinal movement of the type pieces.
10. In a shell marking machine, the combination with the shell holder, of means for forcing the shell holder longitudinally, 60 type-holding means carried by the base of the shell, and a bearing member against which the type of the type-holding means is forced so that each type is brought successively into contact with the bearing member.
